ALPHABETICAL KEYBOARD PUNCH.

Application filed July 28, 1925. Serial No. 46,583.

The present invention relates to punching machines and more particularly to a keyboard controlled punching mechanism for perforating statistical or record cards to 5 represent digits and letters of the alphabet.

Some of the objects of the present invention are to provide a complete unitary keyboard controlled punching mechanism for punching cards in accordance with the letters of the alphabet or other characters or symbols; to provide means in a card punching machine for making a punch set-up corresponding to any letter of the alphabet; to provide means in a card punching mechanism, having a less number of punches in a row corresponding to a card column than there are letters in the alphabet, for perforating the card in a manner to represent any letter of the alphabet desired; to provide a punch mechanism controlled by an alphabetical keyboard wherein operation of any key of one group of letters of the alphabet causes the punch mechanism to function in one predetermined manner, and operation of any key of another group of letters of the alphabet causes the punch mechanism to function in another predetermined manner; and to provide other improvements as will hereinafter appear.

In the accompanying drawings Fig. 1 represents a perspective of an alphabetical keyboard punch embodying one form of the present invention; Fig. 2 represents a section in fragmental elevation showing details 35 of the card punching mechanism and operating adjuncts; Fig. 3 is a diagram of a combination circuit operated by three keys for setting up either or both of two punches; Fig. 4 is an enlarged detail of one 40 of the punch control solenoids and the circuit control for the same; Fig. 5 is a diagram of the keyboard circuits for selectively setting up the punches; and Fig. 6 represents a portion of a card punched in accordance with the present invention to represent 45 certain letters of the alphabet.

Referring to the drawings, one form of the present invention comprises an alphabetical keyboard punch 10 for perforating record cards 11 so that each perforation in a column of the card or a combination of perforations in a column of the card represents either a digit or a letter of the alpha-

bet. In the embodiment of the invention here shown each column in each field of the card has twelve points or places to be perforated arranged in a row, preferably starting at the top of the card with numbers "12" and "11" and then following consecutively from "0" to "9". Since the keyboard 55 12 of the present invention is arranged for number control as well as alphabetical control and has thirty-eight punch control keys (two of the little used alphabet keys are combined for the sake of simplicity) it is 60 obvious that combinations of the key controls are required to produce a perforated condition in a card row corresponding to certain key letters or numerals. In carrying out this identification system the preferred arrangement is such: that operation 65 of any key of the number keys will cause the corresponding number punch for that key to be set up for a punching operation; that operation of any alphabet key from A to M inclusive will cause the setting up of 70 a punch corresponding to the letter key operated in that group; and that operation of any alphabet key from N to Z will cause two punches to be set up in a combination 75 corresponding to the letter key operated in that group. That this may be more readily understood the preferred arrangement is to have the letter key "A" set up the punch 80 corresponding to the numeral "11"; the key "B" set up the punch "0"; the key "C" set up the punch "1"; and thereafter continue 85 consecutively to key "M" which sets up punch "12". For simplifying the key construction the letters "I" and "J" both function on punch "7". The remaining keys for 90 the other group of alphabet letters are arranged as combinations of punch "12" with another punch. Thus the "N" key causes punches "11" and "12" to be set up; "O" key 95 sets up punch "0" and "12"; "P" key sets up punches "1" and "12"; "Q" key sets up punches "2" and "12"; "R" key sets up punches "3" and "12"; "S" key sets up punches "4" and "12"; "T" key sets up 100 punches "5" and "12"; either key "U" or "V" sets up punches "6" and "12"; key "W" sets up punches "7" and "12"; either "X" or "Z" key sets up punches "8" and "12"; and "Y" key sets up punches "9" and "12". 105 It will be understood that this is merely one

arrangement shown by way of example and because it has been found to operate successfully but obviously different combinations can be made either through choice or for 5 different record conditions.

The machine 10 consists generally of a magazine or hopper 13 for holding a stack of the cards 11 which are to be punched, feed rolls 14 for delivering the cards successively to a card passage 15 in a punch unit 16, a set-bar unit 17, and a travelling pin carriage 18, the pins 20 of which are selectively operated by a mechanism controlled by the operation of the keyboard 12. 10 The unperforated cards 11 are delivered through a gate 21 of the hopper 13 by a reciprocable picker 22 which is automatically operated and timed to take off one card at a time and deliver it to the feed 15 rolls 14 from which it enters the passage 15 and becomes properly registered by meeting a stop 23 which is automatically operated and timed, by a rock-lever 24 having a roller 25 in contact with a cam 26, so 20 as to hold the card during the punching operation and then release it for delivery to a receiving hopper 27.

The punching unit 16 consists of a plurality of punches 28, corresponding in number and row arrangement to the lay-out of the card, supported by their heads from a plate 30 and with their shanks arranged for sliding engagement in perforations of punch guide plates 31 and alined respectively with 30 perforations 32 in a die plate 33. The plate 30 is stationary while the plates 31 and 33 are vertically reciprocable so that the card is raised for engagement with the punches 28 and unless a punch is held 35 against movement it will be pushed up by the card and no perforation made in the card. The guide plate 31 and die plates 33 are reciprocated in proper timed relation to the cycle of operations by a rock arm 34 40 having a roller 35 riding on a cam 36.

The set-bar unit 17 performs the function of locking the selected punches 28 against movement as transmitted by the card on the moving die plate 33 and consequently the 45 punches so locked or held are caused to perforate the card. The unit 17 consists of a plurality of setting pins 37 mounted for sliding movement in a box member 38 with the ends of the pins projecting through the 50 top plate of the box and also passing through the bottom plate of the box. Collars 40 and coil springs 41 respectively on the pins 37 retain them pressed upwardly in the box and out of the path of the 55 punches 28 when the latter are moved. The setting pins 37 correspond in number and row arrangement to the punches 28, each pin 37 being superposed and alined with a punch 28.

60 For shifting and holding the setting pins

37 in punch locking position, setting bars 42 are respectively arranged in vertical slidable relation above the setting pins 37, being mounted in a cage frame 43 having a top plate 44, through which the bars 42 protrude, 70 a bottom plate 45, and a reciprocable latch plate 46. Each bar 42 is provided with a shoulder 47 to limit the upward movement of the bar 42, and has two edge recesses 48 and 50 connected by a cam face 51 which 75 abuts the latch bar 46 and causes it to yield and allow the setting bar 42 to move downward to push its punch setting pin 37 to operative position. In this position the bar 42 is locked by reason of the return of the 80 latch plate 46 which then seats in the recess 48 to lock the bar 42 in its down position. After the punching operation all of the latch bars 46 are automatically moved to unlatched position so that the springs 41 of the 85 setting pins 37 restore all set bars 42 to normal position ready for a new set-up.

In order to make a set-up of the setting bars 42, a set-up selecting unit 52 is provided and mounted upon the pin carriage 90 18 so that it travels step by step across the top of the rows of the bars 42, the construction and arrangement being such that the unit 52 moves successively from alined 95 position over the rows of bars 42, stopping over each row to make the desired set-up. The unit 52 as here shown consists of a single row of the pins 20 spaced to aline respectively with the bars 42 of the rows in the setting bar frame 43, and normally held in 100 retracted position by springs 54 operating against pivoted bell crank levers 55 attached to the respective pins 20. The pins 20 are selectively operated by the keys of the keyboard 12 so that any operated key causes its 105 pin 20 to be projected and shift the alined setting bar 42 into latched position so that the corresponding punch is held to perforate 110 the card.

For operating the levers 55 each lever has 110 a flexible rod or piano wire 56 terminating in close proximity to its free arm and the other end of such wire 56 leads respectively to and through the head of solenoid 57 in order to terminate in the path of solenoid 115 core 58. When any solenoid 57 is energized its core 58 will impact upon the end of the wire 56 of that solenoid and move it in the direction of its length to rock its bell crank 55 to throw the corresponding pin 20 outward or downward to shift its setting bar 42 so that the setting pin 37 is moved to prevent movement of the punch 28 which it 120 controls.

In order to energize the solenoids 57 for 125 the selecting operation, a plurality of electrical circuits are provided having a common source of current 60, a switch 61 for control purposes, and a resistance 62 for regulating the operating current and a common cur- 130

rent return 63. The circuits are controlled and closed by the provision of contacts 64 and contactors 65, auxiliary contacts 66 and bridge contactors 67, all so positioned as to be closed respectively by the operation of corresponding keys of the keyboard 12.

As an example of the circuits operated by single keys to cause more than one punch to be set up at a time, reference is had to 10 Fig. 3 wherein letter key "P", number keys "1" and "12", and the punch set-up mechanism for punches "P", "1" and "12" are taken as a sample of the circuits of the group of which these keys form a part. 15 The two solenoids 57 which respectively control the set-up levers 55 are included in a combination circuit, the one being in series with the contact 64 and the contactor 65 of key "1" for making a set-up only for punch "1"; the other being in series circuit with the contact 64 and the contactor 65 of key "12" for making a set-up only for punch "12"; and both solenoids being in parallel circuit with the contact 64, the auxiliary 20 contact 66 and the bridge contactor 67 of the key "P" for making a dual set-up for punches "1" and "12". When two keys, such as "W" and "Q" are represented by the same punches, their contacts 64 are 25 bridged by a conductor 68 so that the operation of either closes the same punch control circuit.

In the operation of the machine a card is automatically fed into registering position 35 in the passage 15 and remains there while the punch set-up for it is made by operating the keys of the keyboard 12 to give the predetermined perforated arrangement. For example, if the first five columns of 40 the card are to be punched to represent the word "Powers", the operation of the key "P" will make a set-up for punches "1" and "12", and the pin carriage 18 will then automatically move over the next row 45 of set-up bars 42 so that operation of the key "O" will make a set-up for punches "12" and "0" in that row. The carriage 18 then moves to the next row and operation of key "W" will make a set-up for punches "7" and "12", and the set-up for letters 50 "E", "R" and "S" being made in the same way and respectively setting-up punches "3", "12" and "3", and "12" and "4". In this way the set-up is made for the entire card 55 and when the carriage 18 has set up the last row required, the punch key of the machine is operated to cause the actuating shaft to be clutched to the motor driven shaft to reciprocate the die plates for the punching 60 operation, the removing of the card stop, and the delivery of the perforated card to the receiving hopper. The carriage 18 is automatically returned to its starting position and the set-up restored to zero position, that is with all the setting pins 37

and setting bars 42 raised to normal or inoperative position.

It will now be apparent that a complete unitary key-punch mechanism has been devised wherein punching of record cards to 70 correspond to letters of the alphabet is made possible or the punching of such cards to correspond to symbols or characters greater in number than has heretofore been possible on a machine of this character. One feature of 75 the present invention is in the provision of a punching machine and an alphabetical keyboard whereby group arrangement of the keys and code control of the punches makes possible the perforation of a card 80 in accordance with any arrangement of letters of the alphabet while provision of the usual numbers still makes possible an arrangement or set-up for punches representing numbers. 85

Having thus described our invention, we claim:

1. In a card perforating machine, the combination of a keyboard mounted on the machine, a punching mechanism including a 90 plurality of rows of punches, each row corresponding to a column of a record card and having a less number of punches than there are keys on said keyboard, set-up bars for the respective punches, a selecting device arranged to travel across said set-up mechanism, automatic means for successively feeding cards to said punching mechanism, means actuated by any one of a group of said keys for causing said selecting device to set 100 two set-up bars predetermined by the keys operated, and means actuated by any one of another group of keys for causing said selecting device to set one set-up bar predetermined by the key operated. 105

2. In a card perforating machine, the combination of a keyboard mounted on the machine, a punching mechanism including a plurality of rows of punches, each row corresponding to a column of a record card and having a less number of punches than there are keys on said keyboard, set-up bars for the respective punches, a selecting device arranged to travel across said set-up mechanism, automatic means for successively feeding cards to said punching mechanism, means actuated by any one of a group of said keys for causing said selecting device to set two set-up bars predetermined by the keys operated, means actuated by any one of another group of keys for causing said selecting device to set one set-up bar predetermined by the key operated, and means for causing all punches corresponding to the set-up bars to simultaneously perforate a 110 card. 115

3. In a card perforating machine, the combination of a keyboard mounted on the machine, a punching mechanism including a 120 plurality of rows of punches, each row cor-

- responding to a column of a record card and having a less number of punches than there are keys on said keyboard, set-up bars for the respective punches, a selecting device arranged to travel across said set-up mechanism, automatic means for successively feeding cards, means actuated by any one of a group of said keys for causing said selecting device to set two set-up bars predetermined by the keys operated, and means actuated by any one of another group of keys for causing said selecting device to set one set-up bar predetermined by the key operated.
4. In a card perforating machine, the combination of a keyboard mounted on the machine, a punching mechanism including a plurality of rows of punches, each row corresponding to a column of a record card and having a less number of punches than there are keys on said keyboard, set-up bars for

the respective punches, a selecting device arranged to travel across said set-up mechanism, automatic means for successively feeding cards to and from said punching mechanism, means actuated by any one of a group of said keys for causing said selecting device to set two set-up bars predetermined by the keys operated, means actuated by any one of another group of keys for causing said selecting device to set one set-up bar predetermined by the key operated, and means for causing all punches corresponding to the set-up bars to simultaneously perforate a card.

Signed at New York, in the county of New York and State of New York, this 9th day of July, 1925.

ALFRED WEILAND.
